(57) **CLAIM**

The ornamental design for a helmet with light display, as shown and described.

DESCRIPTION

A portion of the disclosure of this patent document contains material, which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front view of a helmet with light display showing my new design;

FIG. 2 is a rear view of the helmet with light display;

FIG. 3 is a top view of the helmet with light display;

FIG. 4 is a bottom view of the helmet with light display;

FIG. 5 is a left side view of the helmet with light display;

FIG. 6 is a right side view of the helmet with light display; and,

FIG. 7 is a perspective view of the helmet with light display. The broken lines in the Figures show portions of the helmet with light display that form no part of the claimed design.

1 Claim, 7 Drawing Sheets
